PICTURE RECEIVING BELT BUCKLE

Nicholas J. Savino, Jackson Heights, N. Y., assignor to Exclusive Belt Co., Inc., New York, N. Y., a corporation of New York

Application August 17, 1955, Serial No. 37,531

Term of patent 3½ years

(Cl. D17—1)

Fig. 1

Fig. 1 is a front elevation of a picture receiving belt buckle, showing my new design;

Fig. 2 is a plan view of the same; and

Fig. 3 is a rear view of the same.

The broken lines appearing in Fig. 1 are for illustrative purposes only.

I claim:

The ornamental design for a picture receiving belt buckle, substantially as shown and described.
